UNITED STATES PATENT OFFICE.

AUGUSTO DINA, OF JERSEY CITY, NEW JERSEY, ASSIGNOR TO INTERNATIONAL PROJECTOR CORPORATION, OF NEW YORK, N. Y., A CORPORATION OF DELAWARE.

DESIGN FOR A PEDESTAL SUPPORT FOR A MOTION-PICTURE-PROJECTION MACHINE.

Application filed May 31, 1928. Serial No. 26,915. Term of patent 14 years.

To all whom it may concern:

Be it known that I, AUGUSTO DINA, a citizen of the United States, residing at Jersey City, in the county of Hudson and State of New Jersey, have invented a new, original, and ornamental Design for a Pedestal Support for a Motion-Picture-Projection Machine, reference being had to the accompanying drawing, forming part thereof.

Fig. 1 is a side elevation of a pedestal sup-

port for a motion picture projection machine, showing my new design;

Fig. 2 is a rear elevation thereof;

Fig. 3 is a front elevation thereof; and

Fig. 4 is a top plan view thereof.

I claim:

The ornamental design for a pedestal support for a motion picture projection machine, as shown.

AUGUSTO DINA.
